Attorneys

UNITED STATES PATENT OFFICE.

WILLIAM L. FOSTER, OF DAYTON, OHIO.

FRICITION-HINGE.

1,153,903.

Specification of Letters Patent. Patented Sept. 21, 1915.

Application filed May 10, 1915. Serial No. 26,953.

To all whom it may concern:

Be it known that I, WILLIAM L. FOSTER, a citizen of the United States, residing at Dayton, in the county of Montgomery and State of Ohio, have invented certain new and useful Improvements in Friction-Hinges, of which the following is a specification, reference being had therein to the accompanying drawing.

10 This invention relates to friction hinges for windows, doors and the like, and more particularly to a combined hinge and casement adjuster.

The object of the invention is to provide 15 a means of holding casement sash in any desired position which will be very simple and inexpensive in its construction and will firmly hold the casement in adjusted positions.

20 A further object is to provide such a casement adjuster which will be practically concealed, the only visible portions being the face plates and operating handle.

In the accompanying drawings, Figure 1 25 is a front elevation of a window casing and window showing my invention applied thereto; Fig. 2 is a fragmentary view of the window and window frame with a portion of the latter broken away to show the invention embodied therein; and Fig. 3 is a detail view of the casement adjusting hinge showing the parts separated.

In these drawings I have illustrated one embodiment of my invention and have 35 shown the same as applied to the lower corner of an inwardly swinging sash. As here shown the device constitutes one of the supporting hinges for the sash and the fixed part of the device is mounted in the 40 window frame beneath the sash, but it will be understood that the location of the device is a matter of convenience only and that with but slight modification it can be applied in various positions, for example, 45 when used in connection with a window having a very low sill it will be preferable to arrange the device at a point between the upper and lower hinges where it will be readily accessible for operation.

50 As here shown the device consists of two hinge members, one of which comprises a face plate 1 adapted to be secured to the sash 2, by means of screws or otherwise, and provided with a hinge pin or post 3. In the 55 arrangement here shown this pin, which is arranged parallel with the vertical edge of

the sash, extends below the lower edge of the sash and through the inner sill 4 of the window frame 5. The second hinge member comprises a face plate 6 having arranged in the rear thereof a part 7 having a socket adapted to receive the hinge pin 3, this socket being of such a character that it can be clamped about the hinge pin to grip the same and resist its movement. As here shown this part is in the form of a split sleeve. Mounted on the face plate 6 is an actuating device 8 which extends rearwardly from the face plate and is operatively connected with the split sleeve. Preferably, this actuating device is in the form of a bolt 8 having a shoulder bearing against the face plate and having its rear end screw-threaded into a lug 9 on the outer portion of the split sleeve, the inner 75 portion being held against movement. The outer end of the bolt is provided with a knob or handle 10 by means of which the bolt may be rotated. In the present instance the socket is shown as formed integral with 80 the face plate and when the face plate is secured to the window frame the latter is provided with a recess 11 to receive the clamping member 7.

The operation of the device will be readily understood from the foregoing description and it will be apparent that I have provided an adjusting hinge for a sash or other hinged member which will take the place of one of the usual hinges and which is of such a character that the operating parts, except the knob, are entirely concealed and which can be applied to the sash and frame with but very little cutting, it being only necessary to form the recess to receive the clamping member and an opening to permit the passage of the hinge pin. Further, it will be apparent that the device is very easy of operation and can be actuated to firmly secure the sash in any adjusted position, and moreover, that the device is of such a character it is not liable to be injured should force be applied to the sash without releasing the clamping device. It will further be apparent that while I have shown the device as applied to the lower corner of an inwardly swinging sash it can, with obvious modifications, be adapted to outwardly swinging sash and to different locations on the sash.

While I have shown and described one embodiment of my invention it will be un-

derstood that this has been chosen for the purposes of illustration and that I do not desire to be limited to the details of construction shown and described, for obvious modifications will occur to a person skilled in the art.

Having thus fully described my invention, what I claim as new and desire to secure by Letter Patent, is:—

10. 1. The combination, with a window or door frame having a recess and a sash mounted in said frame, of a hinge member secured to said sash and having a hinge pin, a second hinge member mounted in said recess in said frame and having a part arranged to receive said hinge pin, said part having a clamping action to grip said pin, and an actuating device mounted on the face of said frame and operatively connected 15 with the clamping part of said second hinge member.
2. The combination, with a window or door frame and a sash mounted therein, said frame having a recess beneath said sash and in alinement with one of the vertical edges thereof, of a hinge member comprising a face plate mounted on said frame in front of said recess, and a clamping device mounted in said recess, an actuating device mounted 20 on said face plate and connected with said clamping device, and a second hinge member

comprising a plate secured to said sash and having a pin extending downwardly from said sash and rotatably mounted in said clamping device.

3. A casement adjusting hinge comprising a hinge member having a hinge pin, a second hinge member comprising a clamping device having a socket to receive said hinge pin, an attaching plate to support said clamping device with its socket in alinement with said hinge pin, and an actuating device extending through said attaching plate and operatively connected with said clamping device.

4. The combination, with a window or door frame and a sash mounted therein, of a hinge member comprising a face plate secured to said frame, a split sleeve formed integral with said face plate and mounted in said window or door frame in substantial alinement with a vertical edge of said sash, an actuating device for said split sleeve mounted on said face plate, a second hinge member comprising a plate secured to said sash and having a pin extending downward through said frame and journaled in said split sleeve.

In testimony whereof, I affix my signature.

WILLIAM L. FOSTER.
